UNITED STATES PATENT OFFICE.

LOUIS B. PRAHAR, OF BROOKLYN, NEW YORK.

DESIGN FOR A BUCKLE.

SPECIFICATION forming part of Design No. 21,384, dated March 8, 1892.

Application filed February 5, 1892. Serial No. 420,472. Term of patent 3½ years.

To all whom it may concern.

Be it known that I, LOUIS B. PRAHAR, a citizen of the United States, residing at Brooklyn, in the county of Kings and State of New York, have invented and produced a new and original Design for a Buckle, of which the following is a full, clear, and exact specification, reference being had to the accompanying drawing, forming part thereof, which represents a front elevation of a buckle formed in accordance with my design.

In general outline the buckle approaches the shape of an oval. At each side of the center of the buckle an opening is represented, and that portion of the buckle be-

tween the openings is shaped somewhat as a tongue, which tongue terminates in head figures of fanciful configuration, apparently resting upon or struck up from the body. The body and likewise the tongue are ornamented with figures simulating flowers, and in the heads of the tongue openings are represented.

I claim—

The design for a buckle, substantially as herein shown and described.

LOUIS B. PRAHAR.
